US0D1069413S

(12) **United States Design Patent** (10) **Patent No.:** **US D1,069,413 S**
(45) **Date of Patent:** **** Apr. 8, 2025**

(54) **TOOTHBRUSH**

(71) Applicant: **The Gillette Company LLC**, Boston, MA (US)

(72) Inventors: **Christine Hallein**, Frankfurt (DE); **Soren Jan Wasow**, Langenselbold (DE); **Zhou Pei**, Shanghai (CN); **Zhao Long**, Shanghai (CN); **Lim Jiunn Haur**, Shanghai (CN)

(73) Assignee: **The Gillette Company LLC**, Boston, MA (US)

(**) Term: **15 Years**

(21) Appl. No.: **29/830,296**

(22) Filed: **Mar. 11, 2022**

(30) **Foreign Application Priority Data**

Sep. 13, 2021 (WO) WIPO108515
(51) LOC (15) Cl. 28-03
(52) U.S. Cl. ..... USPC D4/101

(57) **CLAIM**

The ornamental design for a toothbrush, as shown and described.

DESCRIPTION

FIG. 1 is a perspective view of a first embodiment of a toothbrush;

FIG. 2 is a front view thereof;

FIG. 3 is a right-side view thereof;

FIG. 4 is a rear view thereof;

FIG. 5 is a left-side view thereof;

FIG. 6 is a top plan view thereof;

FIG. 7 is a bottom view thereof.

FIG. 8 is a perspective view of a second embodiment of a toothbrush;

FIG. 9 is a front view thereof;

FIG. 10 is a right-side view thereof;

FIG. 11 is a rear view thereof;

FIG. 12 is a left-side view thereof;

FIG. 13 is a top plan view thereof; and,

FIG. 14 is a bottom view thereof.

Broken lines are used in the drawings to designate parts of a toothbrush that form no part of the claim.

1 Claim, 4 Drawing Sheets
